(57) **CLAIM**

We claim, the ornamental design for a buckle for bags, as shown and described.

DESCRIPTION

FIG. 1 is a perspective view of a buckle for bags, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along the lines A-A of FIG. 2;

FIG. 9 is a perspective view of thereof connectable male and female members of the buckle, each being engaged with the corresponding belt of a bag;

FIG. 10 is a perspective view of thereof connectable male and female members of the buckle disconnected from each other;

FIG. 11 is a perspective view of a buckle for bags;

FIG. 12 is a front view thereof;

FIG. 13 is a rear view thereof;

FIG. 14 is a left side view thereof;

FIG. 15 is a right side view thereof;

FIG. 16 is a top plan view thereof; and,

FIG. 17 is a bottom plan view thereof.

The cross hatching showing belt of bag in FIG. 9 is included for the purpose of illustrating the invention in use, and form no part of the claimed invention.
